SPARK PLUG.

Application filed October 27, 1926. Serial No. 144,568.

This invention relates to spark plugs used in ignition systems of internal combustion engines.

More particularly, the invention relates to spark plugs of the self-cleaning type.

Some of the objects of the present inventions are to provide a spark plug of the indicated character with an electrode having an increased spark producing surface, so as to render the spark plug more reliable in operation; to provide novel features of construction whereby carbon accumulations may be removed from the sparking surfaces to insure the desired spark at all times; to provide novel features of construction whereby any accumulation of carbon or oil will be automatically removed from the entire exposed surface of the core insulator after each explosion; to provide novel features of construction in a self-cleaning spark plug which will prevent leakage and therefore loss of power when the spark plug is in use; and to provide a self-cleaning spark plug which may be manipulated mechanically to remove deposits of carbon.

The nature of the invention and its distinguishing features and advantages will appear when the following specification is read in connection with the accompanying drawing, in which:

Figure 1 is a sectional elevation of the spark plug embodying the present invention; the insulator core and its electrode and sparking means being shown in a normal position.

Figure 2 is a view of the plug similar to that shown in Figure 1, but showing the movable parts in the other extreme position.

Figure 3 is an elevation of the lower end of the spark plug.

Referring now more particularly to the several views of the drawing, it will be apparent that, the spark plug, includes a metallic shell 10 having external threads for effecting the attachment of the plug which is a common feature. The shell 10 embodies a ground electrode which would occur at 11. The shell 10 also has a central cylindrical bore 12 which opens into an enlarged circular bore or recess 13, providing a shoulder 14. The bore or recess 13 opens into a larger threaded bore 15, providing a shoulder 16. Extending through the shell 10 is an insulator core 17 which may be of any preferred construction, and is preferably made of por-

celain, and has a collar 18, substantially midway of its length. Extending through the core 17, central thereof, is an electrical conductor or electrode 19. The upper end of the electrode 19 has a cap 20 of conducting material and is pressed in contact with the upper tapered portion of the core 17 as at 21. The cap 20 has a threaded member 22 on which is arranged for threading action, a binding nut 23. The upper extremity of the electrode 19 is formed with a head 24 which prevents the nut 23 from working off the member 22. The collar 18 of the core 17 is disposed in the recess 13, and is adapted to contact with the shoulder 14 to limit the downward movement of the core 17. The core section below the collar 18 is of such length that when the collar 18 is in contact with the shoulder 14 the lower end of the core 17 will be some distance below the lower edge of the ground electrode 11. The lower end of the electrode 19 has a disk 25 of conducting material and is substantially equal in diameter to the diameter of the lower end of the core 17. The said disk 25 is shown integral with the electrode 19, but may be made detachable. The disk 25 lies against the end of the core 17. A clamping nut 26 is employed. The nut 26 is externally threaded so as to fit the threaded bore 15. The nut 26 also has a threaded bore 27. A gasket 28 of any kind, such as copper and asbestos is positioned on the shoulder 16. The clamping nut 26 is screwed down so as to tightly hold the gasket 28 in place on the shoulder 16 to prevent leakage at this point. A compression nut 29 is employed. The body of the nut 29 is threaded so as to fit the bore 27 of the nut 26 whereby the nut 29 will be adjustable with respect to the nut 26. The nut 29 has a central bore 30 slightly larger in diameter than the diameter of the core 17, and said bore 30 opens into a larger bore 31 which provides a shoulder 32. It will be apparent that both nuts 26 and 29 surround the section of the core 17 above the collar 18. A compression spring 33 is employed. The spring 33 surrounds the core 17 and is arranged between the shoulder 32 of the nut 29 and the collar 18 of the core 17. The spring 33 constantly acts on the collar 18 and holds it in engagement with the shoulder 14. This puts the core 17 in its normal position in which the disk 25 will be below the lower face of the ground electrode 11.

11 as shown in Figure 1. In this relationship of the disk 25, when the current is on, a spark will ensue across the gap between the ground electrode 11 and the disk 25, or in portions of the ground electrode 11 and disk 25. The force of the explosion in the engine cylinder, forces the core 17 upwardly against the action of the spring 33, and as a consequence the lower extremity of the core 17 and the circumferential edge of the disk 25 is wiped clean of any carbon which may have been deposited by the burned gases in the cylinder during the explosion. The lower portion of the core 17 and the disk 25 moves in contact with the wall of the bore 12 as shown in Figure 2. When the pressure in the cylinder is relieved, the spring 33 returns the core 17 and therefore the disk 25 to a normal relationship with respect to the shell 10 and therefore the ground electrode 11.

From the foregoing it will be obvious that increased sparking surfaces are provided; that the sparking surfaces and the entire portion of the core insulator, that is exposed to the burning gases in the cylinder during the explosion, are at all times protected from any accumulation of carbon or oil; that the sparking surfaces are at all times protected from any accumulation of carbon; that loss of power as the result of the loss of compression due to leakage through the plug is prevented; and that the resistance of the core to the action of pressure applied thereto may be varied.

35 I claim:

1. A spark plug comprising a metallic

shell which provides a ground electrode and a shoulder; an insulator core extending through said shell, said core having a collar, an electrode extending through said core, a disk of conducting material on the lower end of said electrode extending through the core, a clamping nut adjustably associated with said shell, a compression nut adjustably associated with said clamping nut, and a spring between the collar on the core and the compression nut, the collar engageable with the shoulder of the shell to limit the downward movement of the core, said spring allowing said core to move upwardly so that the circumferential edge of the disk will move in contact with a portion of said shell and thus be wiped clean.

2. In a spark plug, a shell, providing a ground electrode, said shell having a central bore, an insulator core arranged in said bore, said core being equal in diameter to the diameter of said bore; a portion of said core normally extending below the lower face of said ground electrode, an electrode at the lower extremity of the core, said last electrode equal in diameter to the diameter of said bore; and means acting on the core whereby to allow the core to move upwardly under the force of explosion so that the lower portion of the core and the electrode carried thereby will be cleaned by the wall of the bore of any carbon deposited thereon, and said means automatically operable to return the core to its normal position.

EDWARD ALBERT SCHNEIDER.

MORRIS HERTZ.
